(57) **CLAIM**

The ornamental design for cotton swabs for medical instruments, as shown and described.

DESCRIPTION

FIG. 1 is a perspective view of cotton swabs for medical instruments showing our new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a cross-sectional view taken along line 9-9 of FIG. 3; and,

FIG. 10 is an enlarged partial cross-sectional view taken along line 10-10 of FIG. 9.

The broken lines illustrate portions of the cotton swabs for medical instruments which form no part of the claimed design.

The dash-dot-dash-dot broken lines are boundary lines and define the bounds of the claimed design. The claimed design extends to the boundary lines but does not include the boundary lines.
